UNITED STATES PATENT OFFICE.

HARRY L. BEACH, OF COSHOCTON, OHIO.

DESIGN FOR A DISPLAY-STAND.

No. 39,816.

Specification for Design.

Patented Feb. 9, 1909.

Application filed November 7, 1908. Serial No. 461,587. Term of patent 7 years.

To all whom it may concern:

Be it known that I, HARRY L. BEACH, citizen of the United States, residing at Coshocton, in the county of Coshocton and State of Ohio, have invented a new, original, and ornamental Display-Stand, of which the following is a specification.

Reference is had to the accompanying drawing, in which:

Figure 1 is an elevation of the display

stand, showing my new and ornamental design. Fig. 2 is a side elevation of the same.

I claim:

The ornamental design for a display stand as shown.

HARRY L. BEACH.
